MAN'S SHORTS

Herman Zoob, New York, N. Y.

Application April 8, 1939, Serial No. 266,760

1 Claim. (Cl. 2—226)

This invention relates to undergarments and particularly to underwear of the "shorts" or "trunks" type.

The so-called "shorts" quite commonly worn by men are generally made of inelastic woven fabrics which do not stretch sufficiently or have sufficient "back-rise" to accommodate for the various changes in position of the wearer. As a result, they sometimes tend to climb and bind the wearer at the crotch, thus causing considerable discomfort. Likewise, stresses exerted on the undergarment cannot be relieved by stretching of the fabric and, consequently, the garment oftentimes rips or tears. By "back-rise" is meant the ability of the garment to accommodate for bending and similar movements of the wearer which require a greater effective length of the fabric between the waist line and the crotch. To some extent this can be attained by providing greater fullness in the back of the garment, but this fullness must be kept within limits to avoid bagginess, and consequently the probability of insufficient back-rise has persisted.

For certain related types of garments, it has been proposed to overcome these deficiencies by providing panels of knitted fabric in the zones normally subjected to greatest stresses. For example, union suits have been proposed having panels of knitted fabric extending substantially across the entire back of the garment adjacent the waist line for the purpose of increasing the overall extensibility of the garment, permitting greater freedom of movement of the wearer, and particularly, from the waistline to the shoulders.

While such undergarments have improved resiliency, as previously constructed, they have been subject to other disadvantages inherent in their construction. A panel of such length as to extend substantially across the back of the undergarment supports substantially the entire weight of the back of the garment and is subjected to substantially all of the downward stresses exerted on the garment resulting from movements of the wearer. These stresses in a very short time will stretch the panel until its elasticity is impaired, thereby permitting the back portion of the garment to sag. Such panels when used in union suits have also tended, after a limited amount of use of the garment, to tear away from the adjacent portions of the garment usually at the top of the panel. The tendency to sag and tear away has also been increased because the knitted panel as inserted in union suits and the like has been narrowed at each side to such an extent that all the weight of the panel,

and to a large extent the weight of the lower back part and seat of the garment, as well as the stresses thereon, have combined to exert a pull concentrated at the line of attachment of the knitted panel with the waist band or other upper part of the garment. 5

One of the principal objects of the present invention, therefore, is to provide undergarments of the "shorts" type which include a panel of knitted or other elastic material that permits an adequate back-rise in the garment and, at the same time is so disposed that it will not lose its elasticity or tear away from the waistband. 10

Another object of the invention is to provide undergarments of the "shorts" type having a plurality of associated elastic panels which will be adequately supported by the remainder of the garment to prevent loss of their elasticity but which provide sufficient back-rise and stretching to accommodate them to the movements of the wearer. 15 20

Undergarments of the type embodying the invention are characterized by the presence of a gore or panel which provides fullness in the back and seat of the garment and an elastic panel extending across the top of and joining the upper end of the gore to the waistband. The gore extends only partially across the back of the garment and is joined to lateral panels forming the legs of the garment that normally aid in supporting it. The elastic panel thus supports only a portion of the weight of the gore and the back of the garment. The side panels or legs of the garment also tend to support the lateral edges of the elastic panel and thus prevent unnecessary stretching and loss of the elasticity of the panel. 25 30 35

The garment is likewise provided with elastic portions in the waistband which are disposed beyond the ends of the elastic back panel and thus do not tend to stretch this panel laterally, 40 all the lateral stresses being carried by the waistband.

For a better understanding of the present invention, reference may be had to the accompanying drawing, in which:

Figure 1 is a view of the back of a typical form of undergarment embodying the invention, with the garment folded in order to show details of its construction; and

Figure 2 is a side view of the garment shown 50 in Figure 1.

The undergarment disclosed in the drawing consists essentially of a pair of leg portions 10, a back portion 12, a waistband portion 13, and the usual fly portion 14. As illustrated, the legs 55

of the garment are formed of three pieces of material, namely, a front panel 15, which extends from the crotch 16 around and forms the front and part of the back portion of the leg, a trapezoidal or triangular portion 17, forming a part of the back of the leg 10, and the back portion 12 comprising a seat gore 18 of substantially rectangular shape which is joined at its sides to the inner lateral edges of the panels 17. The 5 waistband 13 is joined to the upper edge of each of the front panels 15 and to an elastic panel 19 which is interposed between the waistband 13 and the upper edge of the gore 18. As best 10 shown in Figure 1, the elastic panel 19 has a straight upper edge portion 20, which is joined to the waistband 13, diverging lateral edges 21 and 22, which are joined to the upper part of the 15 back edges of the panels 15, and a reversely curved lower edge 23 which is joined to the upper ends of the trapezoidal panels 17 and the gore 18. The elastic panel 19 may be formed 20 of a resilient knitted fabric or elastic, such as "Lastex," or any other similar type of material which is resilient and tends to return to its initial shape after having been stretched.

The lateral edges 21 and 22 of the panel 19 are prevented from stretching by being joined to the comparatively inelastic rear edge portions of the side panels 15. The panels 17 to a substantial extent support the weight of the gore 18 which extends downwardly and is joined by a transversely extending crotch seam 24 to the forward edges of the panels 15. Since the panels 17 are in turn supported along the sides remote from the gore 18 by the panels 15, it will be seen that the elastic panel 19 supports relatively little of the weight of the back of the undergarment and, as a consequence, is not constantly subjected to tension stresses which would tend to 25 stretch it and destroy its elasticity. Nevertheless the panel 19 can stretch when a stress is exerted on the gore 18 and the panels 17 due to movements of the wearer but returns to its original shape as soon as these stresses are relieved. 30 As shown more clearly in Figure 2, the gore 18 is given a certain fullness while at the same time avoiding bagginess. When this fullness is properly adjusted to fit the buttocks of the wearer, it will be found that as the wearer either bends forward or assumes a sitting position a line of contact of the garment will be established across the buttocks at the beginning of the bending movement, and, owing to the presence of the elastic panel 19 above this line, all or substantially all of the stresses caused by the change of position of the wearer will be exerted in that part of the back of the garment between the line of

contact and the waistband, thus preventing any pull or binding at the crotch.

In order to provide a close and at the same time a comfortable fit of the garment at the waist, the waistband 13 may be provided with 5 elastic panels 25 which are disposed in the side portions thereof, outside of the area of the elastic panel 19. The panels 25, therefore, may be stretched without stretching the panel 19 inasmuch as an inextensible portion 26 of the waistband 13 is joined to the upper edge of the panel 19 and to portions of the panels 15 adjacent to the elastic panel 19.

It will be understood from the foregoing that I have provided an undergarment which has sufficient back-rise or elasticity to permit unrestricted movement of the wearer without pulling down at the waistband or binding at the crotch and which has elastic portions therein so disposed that they will not normally have their elasticity destroyed because of excessive stresses due either to movements of the wearer or weight of the undergarment.

It will be understood, also, that the undergarment may be modified in a number of ways, such as for example, by forming the panels 15 and 17 from one piece of material rather than from two pieces of material, and that various types of materials may be used in the undergarment without departing from the invention. Accordingly, 30 the form of invention disclosed in the drawing and described above should be considered as illustrative only and not as limiting the scope of the following claim.

I claim:

An undergarment comprising a pair of leg portions forming the front, sides and a portion of the back of the undergarment, a waistband having an inelastic portion extending across the back of the garment, said portion adjacent its ends being joined to said leg portions, a substantially rectangular gore joined to said leg portions at the back and cooperating therewith to form a portion, only, of the back and seat, a narrow elastic panel of less length than said inelastic portion interposed between and joined to said inelastic portion and the upper end of said gore, said panel extending beyond the edges of said gore transversely of the back of the garment and being of less length than the width of the back 50 of the garment and elastic portions in the sides of the waistband at points spaced from the ends of said elastic panel whereby said inelastic portion prevents lateral stretching of said elastic panel and said elastic portions permit variation 55 in the size of said waistband.
